SPRING COMPRESSOR

Filed May 23, 1927

UNITED STATES PATENT OFFICE.

LOUIS C. SULLIVAN AND RALPH E. MULLEN, OF DES MOINES, IOWA.

SPRING COMPRESSOR.

Application filed May 23, 1927. Serial No. 193,620.

The principal object of this invention is to provide a coil spring compressor to facilitate the removal and replacement of internal combustion motor valve springs.

More specifically, the object of this invention is to provide a valve spring compressor comprising two hinged jaws designed to engage the spring to be compressed at their free ends and a slideable member engaging 5 the jaws and capable of holding them in a closed position when slid forwardly thereon.

A further object is to provide a valve spring compressor that will securely hold the spring in a closed position without danger of the spring accidentally disengaging 10 itself from the tool.

A still further object is to provide a spring compressor that may be quickly and readily adjusted to springs of various 20 lengths.

A still further object is to provide a tool for compressing springs that is economical in manufacture and durable and efficient in use.

These and other objects will be apparent 25 to those skilled in the art.

Our invention consists in the construction, arrangement and combinations of the various parts of the device, whereby the objects 30 contemplated are attained as hereinafter more fully set forth, pointed out in our claim and illustrated in the accompanying drawing, in which:

Fig. 1 is a perspective view of our complete coil spring compressor ready for use.

Fig. 2 is a side sectional view of our tool with a spring in its jaws and is taken on line 2—2 of Fig. 1.

Fig. 3 is a side view of our tool with an 40 internal combustion motor valve spring in its jaws and illustrates the operation of the same when removing or replacing the spring on the valve stem of a motor.

Fig. 4 is a cross sectional view of the tool 45 taken on line 4—4 of Fig. 3 and more fully illustrates its construction.

Fig. 5 is a cross sectional view taken on line 5—5 of Fig. 2 and more fully illustrates the construction of the free ends of the jaws that engage the spring desired to be compressed.

We have designated the upper jaw of our device by the numeral 10 and the lower jaw 50 by the numeral 11. These two jaws are hinged together at their rear ends by the

upper jaw having inwardly extending ears 12, the lower jaw having inwardly extending ears 13, and a single pin 14 passing through the ears as shown in Fig. 4. The pin 14 extends back around the hinged portion to form a ring 15 which may be used to hang the tool up when not in use. Each of these jaws is of channel form by having inwardly extending side walls 16. The forward end of each of these jaws however, is 60 free from any end walls in order to allow the easy insertion of a coil spring between the jaws. In the forward end of each of these jaws is a longitudinal notch 17 in order that the tool may pass on both sides of 65 a valve stem 18 as shown in Fig. 3. In this illustration, we have designated the engine block by the numeral 19 and the tappet and tappet guide housing by the numerals 20 and 21 respectively. In order that this tool 70 may be easily inserted or withdrawn to compress a valve spring 22 without interfering with the shoulder 23 of the motor block the forward end portion of the upper jaw 10 extends first inwardly and then outwardly. 75

The numeral 24 designates a depression adjacent the marginal edge of the notch 17 in each of the jaws to form a seat for more securely holding the spring in the jaws 80 when the same is compressed. This is especially desirable when inserting a valve stem washer 25 with the valve spring. By this construction, it will readily be seen that if a valve spring is placed between the free ends of the jaws 10 and 11 and the jaws are 85 placed and held in a closed position, the valve spring will be compressed, in which state, it may be easily removed or replaced on the valve stem. The two jaws are formed

with alining longitudinal slots 26 in which is a bolt 27 slidably mounted, having the head 28 engaging the outer side of the lower jaw and a washer 29 engaging the outer side of the jaw 10. This washer 29 is held on the end of the bolt by a key 30 extending 90 through one of the holes 31 in the bolt. The numeral 32 designates an inwardly extending flange on the marginal edge of each of the slots 26 for strengthening the tool and providing a suitable bearing in which the 95 bolt may slide.

When it is desired to compress a spring, it is merely necessary to slide the bolt to the rear of the tool, place the free ends of the jaws over each end of the coil spring and 100 105 110

slide the bolt in its slots toward the free ends of the jaws. By the tendency of the jaws to open there will be enough friction relative to the jaws and the bolt that the bolt will stay in any position it is placed in the slots 26, thereby holding the spring in compressed condition until the bolt is slid backwardly on the tool. To facilitate the sliding of the bolt in its slots, the jaws may be compressed manually by one hand and the bolt moved forwardly or backwardly with the other hand. By this construction, a spring can be compressed or released in a moment's time.

15 Various length springs will require different lengths of bolts. This is easily accomplished in our device by putting the key in different holes 31 in the bolt.

20 The washer 29 fits very loosely on the bolt 27 in order that it may adjust itself to the changing angle of the jaws as the bolt is slid backwardly and forwardly in its slots. The jaws of the tool may be made of any suitable metal.

25 It should be noted that the side walls 16 extend well to the forward end of each of the jaws, thereby preventing the coil spring from slipping sideways out of the same.

Although we have described our tool as

especially adapted to the compressing of valve springs on internal combustion motors, it may be successfully used on other springs desired to be compressed and held in compressed condition.

Some changes may be made in the construction and arrangement of our improved spring compressors without departing from the real spirit and purpose of our invention and it is our intention to cover by our claim any modified forms of structure or use of mechanical equivalents which may be reasonably included within their scope.

We claim:

In a device of the class described, two jaws having their rear ends hinged together, each of said jaws being formed with a longitudinal slot, a pin extending through said slots and having holes in one of its ends, a head integrally formed on its other end capable of engaging the outer side of one of said jaws, a washer loosely mounted on that end of the pin having said holes and capable of engaging the outer side of the other jaw, and a key capable of entering any one of said holes.
